UNITED STATES PATENT OFFICE.

HARRY A. MILLER, OF LOS ANGELES, AND CLARENCE J. CADWELL, OF SANTA BARBARA, CALIFORNIA, ASSIGNEES, BY MESNE ASSIGNMENTS, TO MASTER CARBURETOR CORPORATION, OF DETROIT, MICHIGAN, A CORPORATION OF DELAWARE.

CARBURETER.

1,213,807.

Specification of Letters Patent. Patented Jan. 23, 1917.

Application filed May 4, 1914. Serial No. 836,150.

To all whom it may concern:

Be it known that we, HARRY A. MILLER and CLARENCE J. CADWELL, both citizens of the United States, residing at Los Angeles, 5 in the county of Los Angeles and State of California, and at Santa Barbara, in the county of Santa Barbara and State of California, have invented a new and useful Carbureter, of which the following is a specification.

This invention relates to a carbureter, and one of the main objects of the invention is to provide a novel form of distributor, which is of cylindrical construction and provided 15 with a series of small discharge orifices, which are adapted to be consecutively opened by adjusting the position of the distributor and to thereby regulate the amount of fuel discharged therefrom.

Another object is to provide for a cylindrical construction of as many of the parts as possible in order to enable them to be economically produced on a turret lathe, and to provide a concentric arrangement of 20 the various parts as much as possible to simplify the construction and produce a uniformity in the internal passages to avoid abrupt angles and air currents.

Another object is to provide an air valve 30 concentric of the distributor and operable to control the supply of air and to also directly control the passage of fuel through the distributor.

Another object is to mount the carbureting chamber and its valves revolvably with respect to the float chamber, thereby enabling the fuel in the fitting float chamber to be set at the angle most convenient for attachment to the fuel pipe and permitting 35 the carbureting chamber and parts carried thereby to be placed in the angle most convenient for attachment to the motor.

Another object is to revolvably attach the air inlet chamber to the carbureting chamber 45 to permit the air in the chamber to be readily adjusted into the desired angular position without disturbing the position of the carbureter as a whole.

Referring to the drawings: Figure 1 is a plan view. Fig. 2 is a side view. Fig. 3 is an end elevation. Fig. 4 is a plan view with the mixing chamber, throttle valve, and

air valve removed. Fig. 5 is a section on line x^5-x^5 , Fig. 3. Fig. 6 is a plan view of the air inlet chamber. Fig. 7 is a cross section on line x^7-x^7 , Fig. 6.

The float chamber comprises a barrel 1 which is formed preferably integral with a side barrel 2, the barrel 1 having a cap 3 at its upper end and an integral bottom 4, 60 into which is screwed the upper end of a nipple 5, which has a longitudinal passage 6 and a valve seat 7 and a transverse passage 8, which communicates with the upper portion of a subchamber 9 above a screen 10. A hollow plug 11 is screwed to the lower end of the nipple 5 and retains the subchamber 9 in position.

12 is an inlet socket for the subchamber, and fuel enters therethrough into the subchamber and passes up through the screen 10 and through the transverse passage 8 into the hollow nipple 5, and thence upward into the float chamber 1, its passage into the float chamber being controlled by 75 a vertical needle valve 13, which co-operates with seat 7, and has a grooved collar 14, which engages pivoted arms 15, which are in turn controlled by a float 16, whereby the level of fuel in the float chamber through 80 the medium of the float 16 and arms 15 controls the position of the needle valve 13, and thus regulates the level of liquid therein. By removing the nut 11 and lifting the needle valve, the float chamber may be 85 quickly drained.

17 designates a barrel of the carbureter, which is revolvably connected with the barrel 2, and at its upper end is provided with a suitable flange 18 for connection to the 90 inlet manifold, not shown. The barrel 17 is provided with an annular normal air chamber 18'. Swiveled on the lower end of the barrel 2 is an inlet air chamber 19, which is divided by a partition 20 to form a normal air chamber in the passage 21, which merges with a circular air groove 22, which communicates with an annular air chamber 23, in the barrel 2, the air chamber 23 communicating with the air chamber 18', so that 100 the air in the chamber 19 may be turned to any angle and still maintain communication between the chamber 21 and the annular air chamber 23.

24 is the auxiliary air chamber which communicates with the interior chamber 25.

- Extending into the lower end of the chamber 25 is a hollow arm 26, which communicates with the float chamber, and a plug 27 in the lower end thereof enables the same to be drained, and screwed into the arm 26 is a hollow vertical distributor stem 28. Slidably on the stem 28 is a cylindrical distributor 29 having a closed top 30, and with lateral perforations 31 for the discharge of fuel, which are located at different elevations. Slidably mounted on the distributor 29 is a conical air valve 32 having an under-cut groove 33 in its upper face, which is engaged by the outwardly bent ends 34 of a bail 35, which is pivotally connected to a throttle valve 36 mounted on a shaft 37 in the mixing chamber 38, the walls of the mixing chamber being concave arc portions of a sphere having a greater radius than the radius of the throttle valve 36 to produce a more gradual closing action of the throttle valve as it approaches a shut-off position than if the walls of the mixing chamber were straight. A by-pass 38' is arranged around the throttle valve 36, and the amount of fuel permitted to pass therethrough is regulated by an adjusting screw 39. A by-pass 40 is arranged on the opposite side and communicates with the annular normal air chamber 18' and a thumb screw 41 is provided for regulating the amount of normal air permitted to pass in this manner into the mixing chamber 38. The air valve 32 has a sleeve 42, the upper rim of which acts as a valve to shut off or open the perforations 31 according to the relative position of the air valve and distributor.
- As shown in Fig. 4, the barrel 2 is split at 43, and a screw 44 is provided to contract same and grip the barrel tightly on the barrel 17 to hold the parts rigidly at the desired relative angle. In loosening the screw 44, the parts may easily be adjusted to any angle desired. The lower end of the distributor 29 has pins 45, which are engaged by a forked arm 46 secured adjustably by screw 47 to a shaft 48, the outer end of which has an arm 49 to which is connected a wire 50 for adjusting it. The throttle shaft 37 is provided with an arm 51 for controlling it.
- When the parts stand in the position shown in Fig. 5, the throttle valve is closed and the air valve 32 is moved into its upper position entirely closing off the auxiliary air chamber and practically closing the annular normal air chamber 19 except for a slight space and entirely closing all of the perforations 31 in the distributor so that the suction is exerted through the by-pass 38', and this is supplied from the by-pass 40, but no fuel is permitted to enter the mixing chamber as the fuel passages 31 are all closed. This position of the parts is advantageous

when coasting, and it is desired to prevent escapement of fuel, none at this time being required for operating the motor. For starting the motor, the distributor may be elevated to uncover one or more of the perforations 31, any fuel which may drop into the raised upper portion of valve 32 being lifted therefrom upon suction being established in starting, and the throttle valve is opened the desired amount to permit the normal air to flow from the passage 18' into the mixing chamber 38 and combined therein with the liquid fuel. After starting to increase the speed of the motor, the throttle valve 36 may be opened, and this will move down the air valve 32, which will admit auxiliary air from chamber 25, and will open more of the perforations 31. Thus, the adjusting of the throttle 36 will act to simultaneously control the distributor perforations 31 and also the auxiliary air. It is also possible to increase or decrease the proportion of liquid fuel by adjusting the distributor 29 up or down, or to shut the same entirely off, by moving the distributor 29 down to lowest position. When maximum power is required as for racing, the throttle will be adjusted wide open, which will move the air valve 32 into the lowest position, and the distributor 29 may be adjusted to its highest elevation or at any intermediate point so that all or less of the perforations 31 may be uncovered and the maximum flow of liquid fuel and air is permitted. By shutting off the throttle all of the perforations 31 except one of them will be shut off and this single perforation will supply sufficient fuel to keep the motor turning over, for this purpose, the air being sufficient, which is furnished through the by-pass 40, suction being exerted through by-pass 38'.

What we claim is:

1. In a carbureter, a mixing chamber, an auxiliary air valve for controlling admission of air to said chamber, a distributor slidably within the air valve and having a series of perforations which are adapted to be opened or shut by the air valve according to the relative positions of the air valve and distributor and a throttle valve positioned above the mixing chamber and operatively connected to the air valve.

2. In a carbureter, a mixing chamber, an auxiliary air valve for controlling admission of air to said chamber, a distributor slidably within the air valve and having a series of perforations which are adapted to be opened or shut by the air valve according to the relative positions of the air valve and distributor, a throttle valve above the mixing chamber, an operating member pivoted to the throttle and air valve.

3. In a carbureter, a mixing chamber, an auxiliary air valve for controlling admission

5 of air to said chamber, a distributer slideable within the air valve and having a series of perforations which are adapted to be opened or shut by the air valve according to the relative positions of the air valve and distributer, and means for sliding the air valve along the distributer.

10 4. In a carbureter, a mixing chamber, an auxiliary air valve for controlling admission of air to said chamber, a distributer slideable within the air valve and having a series of perforations which are adapted to be opened or shut by the air valve according to the relative positions of the air valve and 15 distributer, means for sliding the air valve along the distributer, and means for sliding the distributer independently of the air valve.

20 5. In a carbureter, a mixing chamber, an auxiliary air valve for controlling admission of air to said chamber, a distributer slideable within the air valve and having a series of perforations which are adapted to be opened or shut by the air valve according to the 25 relative positions of the air valve and distributer, a throttle valve above the mixing chamber, a connection between the throttle valve and air valve to produce co-operative connection of the throttle valve and air 30 valve, and means for sliding the distributer independently of the air valve.

35 6. In a carbureter, a mixing chamber, an annular normal air chamber for admitting air thereto, an auxiliary air chamber with- 40 in and concentric with the normal air chamber, a distributer for supplying liquid fuel to the mixing chamber, and an auxiliary air valve for controlling the admission of auxiliary air to the mixing chamber, said air valve adapted to control the opening of the normal air chamber, the wall of the carbureter having a by-pass from the annular normal air chamber to a point in the mixing chamber above the annular opening of 45 the normal air chamber in the mixing chamber.

50 7. In a carbureter, a mixing chamber, an auxiliary air chamber below the mixing chamber, an annular normal air chamber surrounding the auxiliary air chamber and discharging into the mixing chamber, a conical auxiliary air valve slideable in the auxiliary air chamber for controlling the admission of air from that chamber to the 55 mixing chamber, and a distributer within the auxiliary air valve in slideable relation thereto, and provided with a series of perforations controlled by the relative position between the distributer and air valve.

60 8. In a carbureter, a mixing chamber, an auxiliary air chamber below the mixing chamber, a normal air chamber surrounding the auxiliary air chamber and discharging into the mixing chamber, a conical auxiliary air valve slideable in the auxiliary air

65 chamber for controlling the admission of air from that chamber to the mixing chamber, a distributer within the auxiliary air valve in slideable relation thereto, and provided with a series of perforations controlled by the relative position between the distributer and air valve, a hollow stationary distributer stem upon which the distributer is slideable for delivering fuel to the distributer, a float chamber, and means for 70 75 conducting fuel from the float chamber to said stem.

90 9. In a carbureter, a mixing chamber, an auxiliary air chamber below the mixing chamber, a normal air chamber surrounding the auxiliary air chamber and discharging into the mixing chamber, a conical auxiliary air valve slideable in the auxiliary air chamber for controlling the admission of air from that chamber to the mixing chamber, a distributer within the auxiliary air valve in 80 slideable relation thereto, and provided with a series of perforations controlled by the relative position between the distributer and air valve, said air valve having an undercut recess in its upper surface, a bail, the ends 85 of which engage in the undercut recess, a throttle valve above the mixing chamber, the upper end of the bail being connected to the throttle valve.

95 10. In a carbureter, a barrel, a liquid distributer therein, an auxiliary air chamber in the barrel, a normal air chamber in the barrel surrounding the auxiliary air chamber, an inlet air chamber swiveled on the lower end of said barrel, said auxiliary air chamber having a partition forming a normal air passage therein communicating with the annular normal air passage of the barrel, and an auxiliary air passage therein communicating with the auxiliary air passage of the barrel.

110 11. In a carbureter, a cylindrical distributer provided with a series of perforations in its wall, means for introducing liquid fuel to the distributer, means for opening and closing said perforations, a throttle valve, said means being connected with the throttle valve for a simultaneous adjustment therewith, the wall of the carbureter having a 115 by-pass formed from the mixing chamber to a point above the throttle valve to permit the passage of a small amount of air around the throttle valve when it is closed, and an adjusting screw for regulating the flow of 120 air through said by-pass.

12. In a carbureter, a mixing chamber, an annular normal air chamber below the mixing chamber, an auxiliary air chamber within the normal air chamber, an auxiliary air valve for controlling the passage of air from said air chambers to the mixing chamber, the wall of the carbureter having a by-pass extending from said annular normal air chamber into the mixing chamber at a point 130

above said air valve, and an adjusting screw for regulating the passage of air through said by-pass.

13. A carbureter comprising a mixing chamber, a fuel distributer in said chamber and having a series of discharge perforations therein, a throttle valve above the distributer, an air valve slidable upon the distributer and controlling the passage of air 10 into the mixing chamber and normally closing the perforations in the distributer, and a connection between the air valve and throttle valve whereby when the latter is opened the air valve opens and uncovers the 15 perforations in the distributer.

14. In a carbureter, a mixing chamber, an annular normal air chamber for admitting air to the mixing chamber, an auxiliary air chamber within and concentric with the normal air chamber, a distributer for supplying liquid fuel to the mixing chamber and having discharge perforations therein, and an air valve controlling the admission of auxiliary air to the mixing chamber and air 20 from the normal air chamber into the mix- 25

ing chamber, said valve being mounted upon and adapted to open and close the perforations in the distributer.

15. In a carbureter, a mixing chamber, an annular normal air chamber for admitting 30 air thereto, an auxiliary air chamber within and concentric with the normal air chamber, said air chamber having communication with the mixing chamber at a common point, a distributer for supplying liquid fuel to the 35 mixing chamber, and an auxiliary air valve controlling the admission of auxiliary air to the mixing chamber, the supply of liquid fuel to the mixing chamber and the air from the normal air chamber to the mixing chamber. 40

In testimony whereof, we have hereunto set our hands at Los Angeles, California, this 28 day of April, 1914.
